United States Patent Office

Des. 185,129
Patented May 12, 1959

185,129

SANDAL SLIPPER OR SIMILAR ARTICLE

Miles Cahn, New York, N.Y., assignor to Gail Manufacturing Co., New York, N.Y.

Application November 18, 1958, Serial No. 53,416

Term of patent 3½ years

(Cl. D7—7)

Fig. 1

Fig. 2

Fig. 1 is a front perspective view of a sandal slipper or similar article, showing my new design.

Fig. 2 is the opposite side of that shown in Fig. 1.

I claim:

The ornamental design for a sandal slipper or similar article, substantially as shown.
